UNITED STATES PATENT OFFICE.

HORACE ERVIE, OF OGONTZ, PENNSYLVANIA.

ANTIRATTLER FOR VEHICLE-DOORS.

1,089,193.

Specification of Letters Patent.

Patented Mar. 3, 1914.

Application filed December 14, 1910. Serial No. 597,245.

To all whom it may concern:

Be it known that I, HORACE ERVIE, a citizen of the United States, residing in Ogontz, Pennsylvania, have invented certain Improvements in Antirattlers for Vehicle-Doors, of which the following is a specification.

My invention relates to certain improvements in means for preventing the sagging of vehicle doors, and the object of my invention is to provide means which will not only prevent the sagging of the doors, but will prevent rattling, so that a neat fit is always secured between the door and the framework, and a further object is to so form the device that it will have a tendency to hold the door closed.

In the accompanying drawing:—Figure 1, is a perspective view, showing sufficient of an automobile or carriage door to illustrate my invention; the door being partly open; Fig. 2, is a vertical sectional view on the line 2—2, Fig. 3, showing the door in the closed position; Fig. 3, is a sectional plan view on the line 3—3, Fig. 2; Fig. 4, is a perspective view of the keeper which is applied to the door frame; Fig. 5, is a perspective view of the projection carried by the door; Fig. 6, is a perspective view of the keeper showing the rollers detached; Fig. 7, is a diagram view showing the projection entering the keeper; Fig. 8, is a diagram view showing the projection forced into the keeper; Figs. 9 and 10, are views illustrating a modification of the projection which is forced between the two flexible rollers; Fig. 11, is a perspective view of a sheathed roller; Fig. 12, is a sectional view of a door frame illustrating a modification of my invention; Fig. 13, is a sectional view on the line 13—13, Fig. 12; Fig. 14, is a perspective view of one of the rollers and its bearing, illustrated in Fig. 12; and Fig. 15, is a sectional view of the roller shown in Fig. 11.

The doors of automobiles, owing to the rocking movement of the car, become loose and out of alinement very quickly so that it is difficult to keep the doors closed and to prevent them from rattling. Guides have been provided to insure proper alinement of the doors with the frame when in the closed position, but these guides do not prevent rattling, which is extremely annoying, as well as hard upon the hinges and latch of the door. By my construction I provide a device which will properly guide the door

and hold it rigidly in its closed position, and which will prevent rattling.

Referring now to the drawings, A is sufficient of a frame of an automobile or carriage to illustrate my invention.

B is part of the door, D is a keeper set in the door frame, and E is a plate secured to the door and having a tapered projection e and shoulders e' , as shown clearly in Fig. 5. The keeper D has two sockets $d-d$, and has a tapered open center d' for the reception of the projection e carried by the door.

$c-c$ are posts projecting through the sockets of the keeper and are provided with heads c' and on each of these posts are sleeves c^2 which turn freely. Mounted on the posts are rubber rollers C made, as clearly shown in Fig. 6, and having countersunk portions c^3 for the heads c' of the posts c . These rollers fit snugly upon the sleeves c^2 and each sleeve, with its roller, freely rotates on the post. When the door is closed the small end of the wedge shaped projection e passes into the opening d' in the keeper and in contact with the roller C, as in Fig. 7. Then, on forcing the door to its closed position the wedge shaped projection e will compress the rollers, as in Fig. 8; the rollers passing back of the shoulders e' , as in Fig. 8, holding the projection rigidly in position and preventing the door rattling. When it is wished to open the door all that is necessary is to use a little force and the projection e is drawn from between the rollers C—C of the keeper; the rollers rolling on their posts so as to quickly relieve the projection from pressure. If the rollers become worn they can be readily removed and other rollers quickly mounted on the posts.

The device can be readily applied to any door of an automobile or carriage and will prevent rattling or sagging of the door, insuring the proper alinement of the lock with its keeper.

The rollers are preferably so proportioned that they will be slightly compressed when the projection e is in place.

In Figs. 9 and 10, I have shown a modification in which the projection e^2 is tapered throughout its length and the rollers are compressed when the projection is in place between the rollers, Fig. 10.

In some instances, in order to prevent the rubber rollers wearing away rapidly, I enclose them in metallic or fiber shells c^4 , Figs. 11 and 15.

In place of the keeper and projection being located at the center of the door, a roller may be located either at the bottom or the top, or at both top and bottom of the door, 5 as indicated in Fig. 12. The bottom roller C' is mounted in a bearing D' secured to the door at the corner and a shouldered plate E' is secured to the sill of the door so that, as the door is closed, the roller rides upon 10 the plate, is compressed, and springs back of the shoulder on the plate E'.

The same construction can be used at the top of the door, as in Fig. 12, in which C' is the roller, D' the bearing on the door, and 15 E' the shoulder plate on the door frame.

I preferably make the tapered projection, which enters the space between the two flexible rollers, notched at the back so that when it is pushed in between the rollers they will 20 expand into the notches and aid in retaining the door in position in the event of the latch not working properly. Furthermore, I may inclose the rubber rollers in metallic or fiber shells in order to prevent the cutting 25 of the rubber by forcing the projection in between the rollers.

In some instances, instead of the two rollers and the projection at the center of the door, they can be mounted either at the top 30 or bottom, or in some instances, as shown in the modification, Fig. 12, one roller may be mounted at the top of the door and the other at the bottom, and in this instance I

also preferably notch the bearing for the rollers so that the rollers will act as a lock 35 when the door is closed.

I claim:

1. The combination in an anti-rattling device for vehicles, of a keeper secured to the door frame; consisting of a plate having 40 two sockets; posts projecting into the sockets; a flexible roller mounted on each post; a transverse slot extending through the keeper; with a plate arranged to be secured to the door and having a lateral wedge-shaped projection with shoulders back of the wedge portion; said projection being arranged to enter the transverse slot in the keeper and projecting between the two flexible rollers; the rollers, when the door is 45 closed, resting back of the shoulders.

2. The combination in an anti-rattling device for doors, of a roller having a rubber center; with a thin shell of yielding material 50 extending around the periphery of the flexible center; with a shouldered projection arranged to engage the roller; one part being mounted on the door and the other on the door frame.

In testimony whereof, I have signed my 60 name to this specification, in the presence of two subscribing witnesses.

HORACE ERVIEN.
